WOODWORKING MACHINE

Harold G. Piper, Lumberton, British Columbia,
Canada

Application July 30, 1935, Serial No. 33,863

3 Claims. (Cl. 144—134)

My present invention relates to improvements in wood working machines and the invention may be embodied in the machine as a unitary part thereof, or the invention may be utilized as an attachment for wood working machines. The primary object of the invention is the provision of means for providing "eased-edges" at the four corner edges of the board, plank, or other stock, which is accomplished eliminating the usual sharp edges and substituting therefor rounded edges.

This rounding of the edges or corners of the stock is attained while the stock is being fed through the wood working machine, as for instance a planer, and the edges are preferably rounded after the surface of the stock has been planed, but while the stock is still being fed through the planer and retained therein.

In carrying out my invention I provide means for applying pressure against the corner edges of the stock by means of which the sharp corner edges are pressed or compacted into or against the body of the stock, and preferably these pressed edges are rounded, or have imparted thereto a convex surface which is smooth and merges with the dressed or finished surfaces of the stock.

In utilizing the device of my invention on stock that is rectangular in cross section I employ two sets or pairs of the presser tools, one set at each side of the stock, and each set of tools "rubs down" or smooths and rounds out the sharp corner edges at one side of the stock.

The invention consists essentially in certain novel combinations and arrangements of parts as will hereinafter be more fully set forth and claimed. In the accompanying drawings I have illustrated one complete example of the physical embodiment of my invention, wherein the parts are combined and arranged according to the best mode I have thus far devised for the practical application of the principles of my invention, but it will be understood that changes and alterations may be made in this exemplifying structure within the scope of my appended claims, without departing from the principles of my invention.

Figure 1 is a conventional view showing the action of the four presser blades, simultaneously, at the four corner edges of a piece of stock that is rectangular in cross section.

Figure 2 is a perspective view of one of a pair of standards or base blocks employed for supporting the tools, it being understood that one of these blocks or standards is used at each side of the stock.

Figure 3 is an enlarged, fragmentary view of a

standard, showing its two presser blades rubbing down complementary corner edges of the stock as the latter is fed through the wood working machine.

Figure 4 is a perspective view of one of the four presser blades showing the bearing face or sharper-groove which contacts with the sharp corner edge of the stock.

Figure 5 is a perspective view of one of the tool holders or presser-blade holders, with the blade omitted.

In carrying out my invention I employ two standards or base blocks, one of which is illustrated in the drawings for use at the right hand side of the planer, and the other, not shown, is used at the left hand side of the planer, or other suitable wood working machine.

The standard 1 is supported above the stock S, which, as indicated, moves or is fed from left to right in Figure 3 in usual manner, as between clamping rolls or guides, and the standard or base block 1 is fashioned with a vertically extending slot 2, and spaced guide lugs 3, by means of which the block may be rigidly fastened, as by bolts, to a stationary part of the wood working machine to which the device of my invention is attached. The base block is vertically adjustable with relation to the stock S in order to adapt the presser tools to different thicknesses of stock, and the presser tools are adjustable for adaptation to various widths of stock.

The base block 1 is fashioned with a laterally extending arm 4, and this arm is provided with a vertically extending socket 5. A similar socket or cylindrical hole 6 is provided in the body of the block, which socket, as indicated, extends diagonally through the body of the block.

In these two sockets the tool holders of a pair of tools are supported, and the holders are shown as pins 7 and 8 having reduced heads 7' to fit in the sockets and shoulders 8' to fit against the supporting arm or against the body of the block. The reduced heads are pierced to accommodate cotter pins 9 that extend transversely through these heads, and the pins 7 and 8 are thus securely mounted in the block, but they are free to turn in their sockets.

The lower, free end of each pin is fashioned with a longitudinally extending slot 10 having opposed flat inner walls, and each pin is provided with a spring 11 coiled about its upper portion, one end of the spring being anchored to a stud 12 rigid with the block, or right with the block-arm, and the other end of the spring is anchored in the slot 10, as indicated. The tendency of the

spring is to turn the pin or holder clock-wise, but the turning action of the spring is limited by the use of a stop lug 13 on the holder-pin and a stop pin or stop lug 14 rigid with the block, or the 5 block-arm and located in the path of the turning movement of the holder-pin.

These holder-pins each have a presser blade 15 mounted in the slotted portion of the pin and the blades are flattened to fit snugly in the slots 10 of the pins. The blades are adjustable in their slotted holders in order that the four blades may be adjusted to point to the four complementary corner edges of the stock S, as in Figure 1, and each blade is fashioned with a concave end 15 forming a curved bearing seat 16. These curved bearing-seats or bearing-faces frictionally engage the four sharp corner edges of the stock, to "rub down" the sharp edges that have previously been formed by the planing tools of the wood 20 working machine.

By means of set screws or bolts 17, or in other suitable manner, the blades, after being adjusted to the proper angles to bear on the corner edges of the stock, are rigidly fixed in their slotted 25 holder-pins.

The holders and the blades are interchangeable and can be employed for use with any one of the four corner edges of the stock, and the use of the slots 10 in the holder pins provides a wide range 30 of angular adjustment with relation to the pins, as well as for longitudinal adjustment of the blades with relation to their supporting holder-pins. As thus arranged, the four presser blades may readily be adjusted to stock of various 35 dimensions, and each blade may be located in the required position to bear against a complementary sharp corner edge, and round that edge to conform to the exact shape and curvature of the other edges of the stock.

40 The springs of the tools tend to swing the working ends of the blades against, or in direction opposite to that of the travel of the stock, and the sharp corner C of the stock is rounded as at R by pressure of the curved bearing face 16 45 on the sharp corner C. The presser blades are automatically swung to operative position by the front end of the stock as the latter moves from left to right in Figure 3. As the front end of the stock contacts with a blade, the latter is 50 swung on the axis of the holder-pin which turns in its socket and thereby places the spring 11 under tension. As the stock is fed through the machine the bearing face 16 rubs on the sharp edge or corner of the stock with sufficient friction, under pressure of the spring 11 to press in, rub down, or compact the sharp edge into a rounded or convex edge that is smooth and which merges with the planed surfaces of the stock.

It will be understood that only a comparatively

slight displacement of the wood is intended, merely smoothing down or rounding off the sharp corner edge of the stock, and therefore no substantial pressure is applied by the tools to displace the stock, and the arrangement of the sets 5 of tools at opposite sides of the stock neutralizes the pressing of the tools in opposite directions. By the use of the springs 11 the presser blades are constantly and continuously held against the corner edges of the stock, throughout the length 10 of the stock, and the blades follow the stock should any lateral or vertical movement occur, and they also follow any irregularities in the surface of the dressed or finished stock.

The degree of compression, within limits, applied 15 by the presser blades to the corner edges, may be varied by varying the tension of the springs 11, and the formation of the rounded or smoothed corner edges may be varied by changing the shape or size of the concave bearing 20 face or groove 16 of the presser blade.

Having thus fully described my invention, what I claim as new and desire to secure by Letters Patent is:—

1. In a device as described, the combination 25 with a base having a socket, a holder-pin having a reduced head journaled in the socket, and means for retaining the head in the socket, of a spring coiled about the pin and having its ends anchored to the base and pin respectively, said 30 holder pin having a longitudinally extending slot, a flat-presser blade mounted in the slot and means for retaining the blade in position, and said blade having a bearing face as described.

2. In a device as described, the combination 35 with a base having a socket, a holder pin having a reduced head journaled in said socket, and means for retaining the head in the socket, of a spring coiled about the pin and having its ends anchored to the base and pin respectively, means 40 on the pin for retaining the same in operable position, said holder pin having a longitudinally extending slot, a flat-presser blade mounted in the slot and means for retaining the blade in position, and said blade having a bearing face 45 as described.

3. In a device as described, the combination with a base having a socket, a holder pin having a reduced head journaled in said socket, and means for retaining the head in the socket, of a 50 spring coiled about the pin and having its ends anchored to the base and pin respectively, means on the pin for retaining the same in operable position, said holder pin having a longitudinally extending slot, a flat-presser blade mounted in the slot and means for retaining the blade in position, and said blade having a concave bearing 55 face as described.

HAROLD G. PIPER.
